Primary Examiner — T Chase Nelson*Assistant Examiner* — Rachel Wolfe(74) *Attorney, Agent, or Firm* — Benoit & Cote Inc.; Charles-Andre Caron(57) **CLAIM**

I claim the ornamental design for triple head solar motion light, as shown and described.

DESCRIPTION

FIG. 1 is a perspective view of the triple head solar motion light in accordance with the present design;

FIG. 2 is a top plan view of the present design;

FIG. 3 is a front elevation view of the present design;

FIG. 4 is a side elevation view of the present design;

FIG. 5 is a rear elevation view of the present design;

FIG. 6 is a bottom plan view of the present design; and, FIG. 7 is a side elevation view of the other side of the present design.

The portions shown in broken lines are for illustrative purposes only and form no part of the design.
